CIGAR BOX OR CONTAINER AND METHOD
OF MAKING THE SAME

Irving E. Black, Brooklyn, and Hyman Jacobstein, New Rochelle, N. Y.; said Black assignor to said Jacobstein

Application October 17, 1938, Serial No. 235,532

6 Claims. (Cl. 93—36)

This invention relates to a cigar wrapper and method of making the same and it is one object of the invention to provide a wrapper of such construction that it can be made by a series of operations which are carried out to form the elements of the wrapper from blank material and then assembled and delivered as a completed wrapper.

Another object of the invention is to provide a wrapper consisting of an inner preserving member of cedar, an intermediate reinforcing member of card board having a ripping member associated therewith, and an outer member, the said members being all formed of sheet material and assembled one upon another in such a manner that a cigar can be very easily wrapped in the inner preserving member, the cutter of the intermediate member being then moved to a position along one side of the cigar and the outer member then wrapped about the inner member and sealed in enclosing relation thereto.

It is another object of the invention to provide a container consisting of superposed members which are formed of sheet material by punching and cutting operations and progressively moved into position to dispose them in their assembled relation to each other where they are firmly secured and cut off and delivered ready for use.

It is another object of the invention to permit the various punching and cutting operations to be performed automatically in step by step operations as sheets of material are moved through a machine and the members then moved into an assembled position and secured to form the complete container which is delivered from the machine ready for use.

Another object of the invention is to provide a cigar container which can be made of sheet material with a minimum of waste and to also reduce to a minimum likelihood of the material being damaged and imperfect containers formed.

Still another object of the invention resides in providing a device which is simple and durable in construction, inexpensive to manufacture and one which will be very efficient in operation and application to use.

With these and numerous other objects in view, our invention consists in the novel features of construction, combination and arrangement of parts as will be hereinafter referred to and more particularly pointed out in the specification and claims.

The invention is illustrated in the accompanying drawings wherein:

Figure 1 is a top plan view showing a cigar wrapped in the improved container;

Figure 2 is a bottom view of the wrapped cigar;

Figure 3 is a view looking down upon the container or wrapper when in a flattened condition;

Figure 4 is a view of the inner container member formed of cedar;

Figure 5 is a view of the intermediate cardboard member;

Figure 6 is a view of the outer member or wrapper formed of tinfoil and waxed paper;

Figure 7 is a view looking at one end of the flattened container;

Figure 8 is a sectional view through the container;

Figure 9 is a sectional view showing the inner member folded about a cigar indicated by dotted lines and the ripping blade of the intermediate member folded to its position at one side of the cigar;

Figure 10 is a sectional view showing the outer member wrapped about the inner and intermediate members and its free end portion in engagement with a flap at its secured end;

Figure 11 is a sectional view showing the contacting flap and free end of the outer member folded to form a closing seam;

Figure 12 is a view looking at one end of the wrapped cigar in the direction of the arrow designated by the letter A in Figure 1;

Figure 13 is a view of the wrapped cigar looking in the direction of the arrow indicated by the letter B in Figure 1;

Figure 14 is a view similar to Figure 1 showing the manner in which the outer member is torn open by the ripping blade;

Figure 15 is a diagrammatic top plan view of a machine for making the container;

Figure 16 is a diagrammatic view in elevation looking at one side of the machine;

Figure 17 is a diagrammatic front elevation of the machine;

Figure 18 is a view illustrating the formation of the outer members;

Figure 19 is a view illustrating the formation of the intermediate members;

Figure 20 is a view illustrating the formation of the inner members;

Figure 21 is a diagrammatic view showing the relation of the intermediate member to the outer member when assembled; and

Figure 22 is a view illustrating the manner in which the cedar for forming the inner members is moistened.

The improved cigar box or container constitut-

ing the subject matter of this invention consists of an inner preserving member 1 formed of cedar, an intermediate reinforcing and ripping member 2 formed of card board, and an outer member or wrapper 3 consisting of sheets 4 and 5 formed of waxed paper and tin foil adhering to each other. These three members are secured in an assembled position, one upon another, and while they have been shown secured by eyelets 6 passing through registering openings 7, 8 and 9, formed in the members, it is to be understood that other securing means may be employed. A slit 10 is formed longitudinally in the intermediate member from its front end to form a ripping blade 11 having its inner end portion united at one side to the body portion of the member. Ends of this intermediate reinforcing member are cut to form substantially circular tabs 12 which are perforated as shown at 13, these tabs being disposed under the companion tabs 14 of the inner cedar member 1 when the members are assembled. Perforations 15 are formed in the rear end portion of the ripping blade and the body portion of the intermediate member is formed with a longitudinally extending slot 16 with which register perforations 17 and 18 formed in the inner member 1 and the outer member 3. The outer member projects beyond the exposed side edge of the intermediate member and this projecting portion which is folded to form a flap 19 is perforated as shown at 20 which register with companion perforations 21 of the outer member when the outer member is wrapped about the enclosed cigar as shown in Figure 10. Additional perforations 22 are formed in the outer member and spaced inwardly from the perforations 21, and at its front end the outer member or wrapper is cut to form a recess 23 which flares towards its open end and exposes the free front end of the ripping blade 11. It should also be noted that the front edge 24 of the inner member 1 is curved longitudinally to provide an inwardly bowed arcuate edge extending across the recess and the protruding end portion of the ripping blade as shown in Figure 3.

When this device is in use a cigar 25 is placed upon the free side edge portion of the inner member and this member which is formed of thin cedar is rolled towards its secured side edge portion to enclose the cigar as shown in Figure 9 and the ripping blade 11 is then turned upwardly to dispose it against a side of the cigar as shown. The outer member or wrapper formed of waxed paper faced with tin foil is then engaged about the enclosed cigar by a rolling operation towards the right in Figure 9 or by drawing the outer member towards the left in this figure until it is disposed about the enclosed cigar as shown in Figure 10 with its free side edge portion in face to face engagement with the flap 19 and the ripping blade held in position against a side of the cigar. The flap and the contacting side edge portion of the outer member are then folded to the position of Figure 11 in which they are disposed flat against the secured side portion of the outer member under the inner reinforcing member with their perforations 20 and 21 registering with the perforations 18 to provide ventilating passages. End portions of the outer member or wrapper which protrude from the cedar inner member or box are then folded upwardly with the tabs 12 and 14 of the intermediate member and inner member so that the folded tabs form ends for the box and the folded portions of the outer wrapper mem-

ber are secured by an adhesive as shown in Figures 12 and 13. In view of the fact that the outer wrapper member is formed with the recess 23 to accommodate the outer free end portion of the ripping blade, this blade will protrude as shown in Figures 1 and 2 from the wrapper a sufficient distance to be easily grasped. The revenue stamp 26 and the identifying band 27 is then applied, and the boxed cigar is ready to be packed in a container from which the individual cigar boxes 10 can be removed. The fact that the inner cedar member has one end cut straight across and its outer end cut with an arcuate edge 24 causes the boxed and wrapped cigar to have the end 28 extend at right angles to its longitudinal axis and its end 29 diagonally thereof. The cigars may, therefore, be placed upright in a pocket of a coat or vest with the ends 29 uppermost and since these ends extend at an incline then will only receive a glancing blow if accidentally struck and will not be liable to be broken or knocked from the pocket by the force of the blow. When it is desired to smoke a cigar the protruding end portion of the ripping blade is grasped and pull exerted to tear the outer wrapper member longitudinally as shown in Figure 14. This will not only cause the outer wrapper member to be torn longitudinally and permit easy removal of the cigar but also cause the revenue stamp to be torn and thus destroyed as required by law.

In Figures 15 through 22 there has been illustrated an apparatus for making the improved individual cigar box or container and the method steps followed during such manufacture.

This apparatus consists of a frame which may be referred to as substantially T-shaped in top plan as it has a portion 30 and a cross portion 31 extending at right angles to the portion 30 in crossed relation thereto. This frame or table is supported by a suitable number of legs 32, and upon referring to Figures 16 and 17 it will be seen that the portion 31 has a single upper platform or table top 33 whereas the portion 30 has an upper platform or table top 34 and a lower platform or shelf 35 which extends longitudinally of the portion 30 but is of less length than the platform 34 and at its front end intersects the lower end of an upwardly extending forwardly inclined portion 36 leading to a transversely extending slot 37 formed in the platform 34.

The roll 38 of material for forming the outer wrapper members is mounted at one end of the platform 33 by supporting brackets 39 and below the roll 38 these brackets support a deflecting roller 40 for directing the stock or strip 41 longitudinally of the table or platform along which it is drawn by a suitable number of feed rollers 42. This strip consists of companion sheets of waxed paper and tin foil with the waxed paper uppermost as the strip moves along the table and the feed rollers will advance the strip in step by step movements during formation of the container. The steps or stages followed during formation of the outer wrapper member and assembly thereof with the intermediate and inner members have been indicated in Figures 17 and 18 by the numbers 1 through 8 as shown at 43. The first (1) stage consists of a blank portion of the strip and at the second (2) stage the perforations 9 are formed through the strip adjacent one side edge thereof by the piercing punches 44 and notches 45 are formed at opposite side edges of the strip by notching punches 46. The strip is then advanced for the third (3) stage or step where the perforations 18, 20, 21 and 22 are formed 75

near opposite side edges of the strip by piercing punches 47 and an opening 48 for forming the notch or recess 23 is formed by a notching punch 49. At the stage or step four (4) the marginal portion 5 of the strip through which the perforations 20 are formed is folded downwardly by a folding punch 50 through the widened end portion 51 of the slit 52 to form the depending flap 19 and the strip is then advanced through the stage or step five (5) as a finished blank ready for assembling to the stage or step six (6) where it is assembled with the intermediate and inner members and the eyelets 6 applied and clinched by eyeleting device 53. The strip with the intermediate and inner members then passes through the feed rollers 42 at the stage or step seven (7) and advances to the stage or step eight (8) where the end blank is cut off by the cutter 54 across the wider end of the opening 48 and not only cut the end blank free from the strip but also provide the outer member with the recess or notch 23.

The intermediate reinforcing members which are of cardboard are formed from a strip 55 which is mounted as a roll 56 at the rear end of the platform or shelf 35 and guided therefrom onto the platform by the deflecting rollers 57. Feed rollers 58 move the cardboard strip along the platform in step by step movements to the lower end of the inclined portion 36 up which it passes and between the deflector rollers 59 onto the table 34 under the inner members which are formed thereon. The cardboard strip 55 passes through nine steps or stages to form the intermediate or reinforcing members and assemble them with the companion outer and inner members, and these steps are shown in Figure 19 where they are designated by the numbers 1 through 9 as indicated at 60.

The first stage (1) consists of a blank portion 40 of the strip which at the second stage (2) is operated by the punches 61 to form the perforations 8, 13 and 15. At the third stage (3) the punch 62 forms the slot 16 after which the strip is moved through a blank stage (4) to the stage (5) 45 where a portion of the strip at one side thereof, which is indicated by dotted lines and designated by the numeral 63, is cut away by notching punch 64 to partially form one tab 12 and the adjacent end of the ripping blade 11. The strip then advances to stage six (6) where it is operated upon by punches 65 to complete the partially formed tab 12 and adjacent the other side edge of the strip form an opening 66 to partially form the second tab 12 and the adjoining end of the intermediate member. After the opening 66 has been 50 formed the strip is advanced to the next stage (7) where the punch 67 enlarges the opening 66 as shown at 68 to complete formation of the tab and adjoining end of the intermediate member, the strip being then advanced to stage (8) where the punch 69 cuts the strip as shown at 70 to 55 provide the slit 10 separating the blade 11 from the body portion of the intermediate member when the portion 71 is cut off to free the blade at its front end. After the slit 70 has been formed the strip is moved upwardly along the inclined portion 36 of the platform and between the deflecting rollers 59 through the slot 37 onto the forward end portion of the blade 34 where it 60 moves forwardly under the inner members to its stage (9) which places it over the outer member 3 at the stage six (6) thereof where it is secured by the eyelets and at the same time severed from the strip by the cutter 72 which not 65 only cuts a finished intermediate member from

the strip 55 but also cuts off the portion 71 and leaves the ripping blade with a free front end extending into the recess or notch 23 of the outer member 3. The portion 71 is left in place until the finished intermediate member is cut off as 5 otherwise these members would only be connected with each other at the attached ends of the blades and would be liable to be torn apart during movement up the inclined portion 36 of the shaft or table 35 and along the forward portion of 10 the shelf 34 into position under the cutter 72.

The inner members 1 are formed from long strips 73 of very thin cedar having the grain extending transversely thereof, and these strips are piled in a stack upon a shelf 74 extending from 15 the rear end of the table 34 flush with the upper face thereof. The cedar strips 73 which are of greater length than the distance between the feed rollers 75 and 59 are manually fed from the stack toward the rollers 75 for engagement between the 20 same, but before reaching these feed rollers, they pass between the rollers 76 of a moistener 77 as shown in Figures 16 and 22. The cedar will thus be moistened and rendered flexible so that it will not be liable to split longitudinally of its grain 25 which extends transversely of the strip but longitudinally of the finished inner members.

During formation of the inner members the strips 73 are advanced along the table 34 towards the forward end thereof first by action of 30 the feed rollers 75 and then by the feed rollers 59 which grip the forward end of a strip before the rear end thereof moves from between the rollers 75. Between the rollers 75 and 59, the strips are each subjected to a series of operations in 35 steps or stages designated by the numbers 1 through 4 as indicated at 78. At the first stage (1) the strip is blank but when the strip is advanced to the second stage or step (2) it is operated upon by the perforating punches 79 to 40 form the perforations 7 and 17. The strip is then advanced to the third stage (3) where its side edge portions are cut by the notching punches 80 and during this operation each side edge portion of the strip is cut to form the straight cut side edges and the arcuate side edges 24 of the inner members and partially form the tongues 14 which are completed during the next cutting of the strip at the stage (3). This completes formation of the inner member which is then advanced to the stage (4) and from this point the strip is progressively advanced as a series of 45 connected inner members to the front end of the table 34 where the forward one moves into place over the intermediate member and the outer member and as the perforations 1, 8 and 9 will now be in alignment, the eyelets may be passed through them and clinched to hold the three members assembled. During the clinching operation the intermediate and inner members will be cut from their strips and the assembled members then moved as a unit along the table 33 to the position where the outer member will be severed from its strip by the cutter 54 and the completed device will be discharged ready 50 for use.

It will be understood that during the various operations the strips from which the three members are formed are shifted in step by step movements such distances and in such timed relation 70 to each other that when the strip of outer members reaches the point of assembly opposite the front end of the table 34 the intermediate and inner members will move into place over it in proper relation to the outer member and each 75

other to dispose the openings 7, 8 and 9 in alignment for insertion and clinching of the eyelets 6. It will also be understood that while the three members have been shown secured by eyelets other means may be employed and that the invention is not restricted to the detailed construction of the apparatus for operating upon the strips from which the three members are formed.

From the foregoing description of the construction of our improved device, the operation thereof and the method of applying the same to use, will be readily understood. It will be seen that we have provided a simple, inexpensive and efficient means for carrying out the objects of the invention and while we have particularly described the elements best adapted to perform the functions set forth, it is obvious that various changes in form, proportion and in the minor details of construction may be resorted to, without departing from the spirit of sacrificing any of the principles of the invention.

Having thus described the invention, what is claimed is:

1. The method of making a container having an outer member, an intermediate member, and an inner member comprising independently shifting strips of material in step by step movements into position to dispose portions of the strips in superimposed relation to each other, independently operating upon said strips during movements thereof to form duplicate connected members of predetermined outline, securing the superimposed members in predetermined relation to each other, severing the inner and intermediate members from the strips from which they are formed, and severing the outer member from the strip from which it is formed.
2. The method of making a container having an outer member, an intermediate member, and an inner member, said method comprising providing strips of sheet material, independently shifting said strips in step by step movements towards an assembly point, operating upon said strips as they are moved towards the assembly point to form of each strip a plurality of interconnected duplicate members, disposing the intermediate members formed from one strip upon the outer members formed from another strip and disposing the inner members formed from a third strip upon the intermediate members at the point of assembling, securing the superimposed members to each other, severing the intermediate and inner members from the strips from which they are formed, and severing the outer member from the strip from which it is formed.
3. The method of making a container having an outer member, an intermediate member and an inner member, said method comprising providing strips of sheet material, operating upon the strips to form the said members, and shifting the strips into position to dispose an inter-

mediate member upon an outer member and an inner member upon the intermediate member, securing the assembled members, detaching the intermediate and inner members from the strips from which they are formed, and detaching the outer strip from the strip from which it is formed.

4. The method of making a container having an outer member, an intermediate member and an inner member, said method comprising providing strips of sheet material, disposing one strip over a second strip longitudinally thereof and a third strip transversely of the first and second mentioned strips, independently shifting the strips longitudinally into position to dispose end portions of the first and second mentioned strips over the third strip transversely thereof in spaced relation to its end, subjecting said strips to punching and cutting operations as they are moved longitudinally to transform the strips into the said members, securing the intermediate and inner members upon the outer member and severing the inner and intermediate members from the strips from which they are formed, and severing the outer member from the strip from which it is formed.

5. The method of making a container having an outer member, an intermediate member and an inner member, said method comprising providing strips of sheet material, disposing one strip over a second strip longitudinally thereof and a third strip transversely of the first and second mentioned strips, shifting the strips longitudinally independent of each other predetermined distances and at predetermined speeds to dispose end portions of the first and second mentioned strips over the third strip and during shifting of the strips operating upon the same to transform the strips into the said members of predetermined configuration, securing the said members to each other one upon another, and severing the members from the strips from which they are formed.

6. The method of making a container having an outer member, an inner member, and an intermediate member, said method comprising providing a strip of paper and metal foil and shifting the same longitudinally, operating upon said strip to form connected outer members thereof, disposing a strip of cardboard and a strip of cedar transversely of the first strip and shifting the same longitudinally while operating upon the same to form connected inner members of the cedar strip and connected intermediate members of the cardboard strip the said inner and intermediate members being moved into place upon the outer member and secured thereon with the inner member over the intermediate member, and said members being severed from the strips from which they are formed.

IRVING E. BLACK.
